[57] CLAIM

The ornamental design for a partial-cover carton for a flash camera, as shown and described.

DESCRIPTION

FIG. 1 is a front elevational view of a partial-cover carton for a flash camera showing our new design;

FIG. 2 is a top plan view thereof;

FIG. 3 is a bottom plan view thereof;

FIG. 4 is a right-side elevation view thereof;

FIG. 5 is a left-side elevation view thereof;

FIG. 6 is a perspective view of the partial-cover carton of FIGS. 1-5 placed on the flash camera (shown in phantom), as seen from the front, top, and right-side of the flash camera; and,

FIG. 7 is a perspective view of the partial-cover carton of FIGS. 1-5 placed on the flash camera (shown in phantom), as seen from the rear, bottom, and left-side of the flash camera.

The broken line showing of the flash camera on FIGS. 6 and 7 is for illustrative purposes only and forms no part of the claimed design.
